UNITED STATES PATENT OFFICE

2,539,936

BAND PLACING APPARATUS

William H. Taylor and David S. Eaton, Pawtucket,
R. I., assignors to The Clark Thread Company,
Inc., a corporation of Delaware

Application April 4, 1946, Serial No. 659,502

1 Claim. (Cl. 93—93)

1

This invention relates to a novel and improved band placing apparatus, the novel features of which will be best understood from the following description and the annexed drawings in which we have shown a selected embodiment of the invention and in which:

Fig. 1 is a side view of an apparatus having the invention embodied therein;

Fig. 2 is a side view in partial section of the apparatus illustrated in Fig. 1 at a different stage of operation, certain parts being omitted for the sake of clarity;

Fig. 3 is similar to Fig. 2, but shows the apparatus at another stage of operation;

Fig. 4 is a front view, sectioned approximately along the line 4—4 of Fig. 1, of the apparatus illustrated in the foregoing figures;

Fig. 5 illustrates a banded skein of thread or yarn;

Fig. 6 is a view on an enlarged scale taken approximately on the line 6—6 of Fig. 1, certain parts being omitted for clarity; and

Fig. 7 is a view taken approximately on the line 7—7 of Fig. 2, certain parts being omitted for clarity.

The apparatus embodying our invention, as illustrated in the present application, operates in conjunction with a band forming apparatus which is the subject of our copending application Serial No. 659,501, filed April 4, 1946, now abandoned. Apparatus of the same general type is shown in the patent to Taylor and Kershaw No. 2,151,340 on which this is an improvement.

In the drawings, corresponding parts in this application and in our copending application Serial No. 659,501, filed April 4, 1946, have been assigned similar numerals in both cases so that the sequence of operations may be more easily understood. Similar parts in the various figures are identified by similar numerals throughout.

Referring now to the drawings, the skeins 4 may be formed of yarn or thread on a skein forming machine such as shown in the patent to Taylor and Kershaw No. 2,246,608. In such a machine, the skeins 4 are intermittently moved to various positions during the operation of the machine by a chain conveyor 5. When a skein 4 reaches the bottom position of the conveyor, a pair of bands 16 and 16a are placed on the skein while it is in this position and prior to removal of the skein from the skein forming machine. These bands may be placed at each end of the skein as shown, for example, in Fig. 5.

The bands 16 and 16a may be of different widths and may be formed, as mentioned, by the appa-

2

ratus described in detail in our copending application Serial No. 659,501, filed April 4, 1946. In such a case, the bands are formed on the arms 12 of a turret 13 which is intermittently rotated to bring a band carrying arm into alignment with the bottom skein on the conveyor at a position indicated by the numerals 12—B. The bottom skein is held in accurate alignment with the turret arm during the initial movement of the band onto the skein by a pair of clamping fingers 110 which are controlled by a linkage indicated generally at 111. The linkage 111 is operated by a cam 38 which is driven by a cam shaft 41. This mechanism is described in detail in Patent No. 2,151,340.

As shown in Figs. 1 and 6, a pair of grippers 57a are disposed on either side of the band 16 on the turret arm 12 when it is at position 12—B. These grippers are carried by a pair of arms 57 which are pivoted on a guide rod 112 as a common center. A spring 114 acts on the arms 57 so as to normally urge the grippers 57a into engagement with the band.

The jaws formed by the arms 57 may be forced open by means of a spreader bar 91 which is disposed between the arms 57. The spreader bar 91 is pivotally mounted at its ends in brackets 97 and may be rocked by a lever 92 secured to one end of the bar. The lever 92 is connected by a link 93 to a cam arm 94. The cam arm 94 is pivoted to the frame at 95 and carries a cam roller 96 intermediate its ends. The cam roller 96 engages with a cam C on a cam shaft 103.

The cam shaft 103 is driven through gears 104, 105, 106 and 107 from another cam shaft 102 which is driven by a drive shaft 100. These gears have a 2 to 1 ratio and drive the shaft 103 at double the speed of the shaft 102.

The arms 57 carrying grippers are moved lengthwise of the turret arm and of the skein along the guide rod 112. This movement may be caused by a cam D which is rotated by the shaft 102. The cam D engages with a roller 115 on a cam arm 116 which is pivoted on the frame at 116'. The cam arm 116 carries at its other end a gear segment 117 which may be secured in a desired position by a screw 113. The gear segment 117 engages with a gear segment 118 formed on one end of a lever 119 which is pivoted on the frame at 120. The arm 119 is slotted and carries a roller 121 which may be adjustably positioned along said arm. The roller 121 engages with a slot in a lever 122, one end of which is pivoted on the frame at 123 and the other end of which is forked. The forked end of the lever 122 engages

with the gripper arms 57 through links 124 and pusher bars 125.

By adjusting the position of the roller 121 on the arm 119 and appropriate adjustment of the gear segment 117, the throw of the lever arm 122 may be varied for any given movement of the arm 119. The cam D and the arrangement of the levers, as illustrated, are arranged to cause a relatively long movement of the lever arm 122 and then a relatively short movement of the lever arm 122 during each revolution of the cam. By this arrangement a band will be placed at each end of the skein.

The cam roller 115 is held in engagement with the cam D by a tension spring 126 which is connected to the lever arm 122 and the frame of the machine.

While the invention has been shown as embodied in a specific form of apparatus, nevertheless it is to be understood that it may be embodied in other forms of apparatus and, therefore, it is not intended to limit the invention except by the appended claim.

We claim:

In an apparatus of the character described wherein skein-holding bands are placed at spaced points on a skein supported in a banding position in a skein-forming machine, the combination which includes a pair of band-gripping fingers, said band-gripping fingers being reciprocable between a band-engaging position and a plurality of band-placing positions, a double-acting cam for actuating said fingers, said cam having a surface

for reciprocating the band-gripping fingers between the band-engaging position and a first band-placing position and a second surface for reciprocating the band-gripping fingers between the 5 band-engaging position and a second band-placing position spaced from said first band-placing position and a linkage connecting the band-gripping fingers to the cam, said linkage including a pair of pivoted levers, one of said levers having 10 a slotted opening therein and the other of said levers having a roller adjustably positioned thereon and engaging with the slotted opening in the other lever, the position of said roller determining the distances said gripping fingers are moved 15 by said linkage in reciprocation between the band-engaging position and the first and second band-placing positions.

WILLIAM H. TAYLOR.
DAVID S. EATON.
